ATTORNEY.

UNITED STATES PATENT OFFICE.

MATTEO DE CESARE, OF NEWARK, NEW JERSEY, ASSIGNEE, BY MESNE ASSIGNMENTS,
TO VOICES INCORPORATED, A CORPORATION OF DELAWARE.

SOUND-REPRODUCING DEVICE.

Application filed March 21, 1923. Serial No. 626,617.

The invention relates to improvements in sound producing devices and more particularly to such devices adapted to be positioned within a doll or toy.

5 The main object of the invention is to provide a device of this character which is not only simple and efficient in operation, but which also lends itself to easy and cheap construction.

10 Further and more specific objects, features and advantages will more clearly appear from the detail description given below taken in connection with the accompanying sheet of drawings which forms a part of this 15 specification. In the drawings which illustrate a preferred embodiment of the invention:

Figure 1 is a vertical section through the housing, diaphragms and bellows, showing 20 the valve or door in its relation to the trip mechanism.

Figure 2 is a plan with the cover removed.

Figure 3 is an end view of the valve and the trip mechanism.

25 Figure 4 is a modified and preferred form of a trip.

Figure 5 is a view showing the trip in its relation to a modified type of valve or door.

Figure 6 is a side view of the form shown 30 by Figure 5.

Figure 7 is a plan of the form shown by Figure 6.

Referring now to the drawings, wherein like reference characters designate corresponding parts throughout the several views, 35 5 designates a cylindrical housing and 6 the bottom flanged closure therefore, which may be formed separable or integral therewith as manufacturing necessities may require.

40 Within the housing there is provided a stationary lower diaphragm 7 which has secured thereto a bottom plate 8, the tongues 9 of said plate extending through recesses in the bottom closure 6 and said tongues are bent

45 flush with the bottom to as to rigidly secure the diaphragm 7 in position within the housing. A top or movable diaphragm 10 is connected to the bottom diaphragm 7 by the normally collapsed bellows 11, it being ob-

50 served that the bottom of said bellows extend about the periphery of the diaphragm 7 so that the said bellows are clamped by the plate 8. That is, the lower edge of the bellows 11 as viewed in Fig. 1, is turned in-

55 wardly underneath the edge of the bellows

head 7 and is clamped thereto by the metal disc member 8, so that the inwardly turned lower edge of the bellows is clamped between flat surfaces of the head 7 and disc 8 at the peripheries thereof. The upper edge of the bellows 12 is secured in any well-known manner within the grooved portion of the diaphragm or weighty head 10. Formed preferably integral with the diaphragm 10, I have provided a frustro-conical extension 13 having an aperture 14 in the top thereof and within the bottom of said conical member and the head 10, a cylindrical cup 15 is positioned which cup extends below the said head 10 and within the bellows 11. A horizontal tube 16 provided with a suitable reed, provides communication between the interior of the bellows and the cup 15 for the passage of the air that is drawn into the bellows when the same are extended.

70 The conical extension 13 is provided with the band or collar 19 secured by a screw 20 and hingedly connected as at 21 to the band or collar, I have provided a valve, closure or door 22 which controls the escape of the air trapped within the bellows when the same collapse from their extended position. A guide rod or bar 24 is secured at its lower end to the diaphragm or head 7 and extends through a recess or aperture centrally of the upper diaphragm or weighty head 10 so as to permit the latter to slide on said bar when the bellows are extended and are collapsed, it being of course understood that the diaphragm or plate 10 is of heavy material such as lead and consequently when the entire device is inverted and tilted from one position to the other, the said diaphragm or head 10 will fall by gravity so as to collapse the bellows and of course force the trapped air to escape past the valve 22.

75 In the form shown by Figures 1 to 3 inclusive of the drawings, the valve 22 which is hingedly connected as at 21 to the band 19 is normally closed by the spring 26, one end of which is connected to said band and the opposite end to the valve. The said valve 22 is rectangular and the outer end of the same is bent slightly upwardly and provided with a rectangular slot or recess 27 to 80 permit of the vertical movement of said valve upon the opening and closing thereof as the head or plate 10 is actuated upon the tilting of the device. The said valve or door 22 is also provided with a downwardly 85

90 95 100 105 110

struck finger 29 on the inside of the recess or opening 27.

Secured to the upper end of the guide bar 24, I have provided a double tripping element, which in the form shown by the Figures 1 to 3, consists of a flat strip 30, the upper end of which is provided with a tongue 31, adapted to pass through an aperture 32 and bent so as to be secured on the bar. Substantially intermediate the upper and lower ends of the strip, there are provided the arms 33, 34 which are bent or wrapped about the guide bar 24, the said arm 34 having an outwardly bent prong or projection 35 which is adapted to engage the finger 29 so as to trip and to open the valve 22. The lower end of the strip 30 is bent slightly outwardly and terminates in a substantially horizontal stop 37 which trips the valve 22 after the same passes the first trip above referred to. With the parts as shown in Fig. 1, the weight 10 will drop by gravity and compress the bellows so that air will be forced out of the bellows through the reed pipe 16 causing the reed to sound and the sound therefrom will issue into the sound chamber of the frusto-conical extension. During the first part of the collapsible movement of the bellows the valve 22 will be opened by the engagement of the finger 29 with the projection 35 so that the sound is free to issue through the opening 14 and out of the device through the fabric covering on top thereof. As the bellows is further compressed by the weight 10 the finger 29 will slip off of the projection 35 thus permitting the valve 22 to close the opening 14 and so terminate the sound from the reed pipe. As the bellows is further compressed by the weight 10 the outer end of the valve 22 will engage the stop or projection 37 and so cause the valve 22 to be again opened whereby a second syllable will be heard from the reed pipe during the last part of the collapse of the bellows. When the bellows are fully extended, the valve 22 will be disposed slightly above the first trip 35 and since said valve is free to open, a very slight escape of the air will be effected, just before the valve 22 is initially tripped. The first sound produced is that of the phonetic sound in pronouncing the letter "M", which broadens out when the valve 22 is first tripped quickly to the pronunciation of the letters "Ah." The slight interval between the first trip and the second trip also produces a sound of the letter "M" and when the valve 22 is tripped the second time, and as the diaphragm or plate 10 drops to its lowermost position, the sound produced will be that of the letters "Ah", but this sound will be somewhat prolonged. When the device is inverted the weight 10 will return to the position shown in Fig. 1 and the bellows will be distended. During this movement the finger 29 will slip past the pro-

jection 35 owing to the beveled or slanting position of the finger 29 and the fact that the valve 22 has some side play in its pivotal connection permitting the valve to move sideways sufficiently for the finger 29 to pass the projection 35. After thus passing the projection 35 the valve will be returned to its normal position as shown in Figs. 1 and 2 by the tension spring 26. Consequently, each time that the device is inverted or turned upside down and then returned to its operative position, the sound of "Ma-Ma" will be produced as above described. As a substitute for the tripping device shown in Figures 1 to 3 of the drawings, I have devised a very efficient manner of tripping the valve 22 by utilizing a clip designated in its entirety by numeral 38, one end of the clip 39 passing through an aperture or recess 40 in the upper end of the guide bar 24 and bent thereon. The clip extends outwardly to one side of the bar and is curved as indicated at 41, which constitutes the trip and the equivalent of the tongue 35 heretofore referred to. The opposite end of the clip extends through a recess in the bar 24 and is bent downwardly as indicated at 43 and terminates in a substantially horizontal extension 44 which is somewhat below the bent portion 41 of said clip and the said extension 44 corresponds with the portion 37, being of a length to permit of the sliding movement of the outer end of the valve 22 as the same gradually opens to effect the prolonged sound as above explained.

In Figures 5, 6, and 7, I have shown an arrangement having a still further modified valve operating arrangement wherein a tripping device or clip is bent or crimped on the bar 24 to provide a hooked end 41^a, said clip having a step-down portion 42^a on the opposite side of the bar 24, which clip is designed for use in connection with a particular type of valve shown at 45, hinged connected in the same manner as the valve 22 above referred to. The valve 45, however, is provided with a finger 46, which cooperates with the hook 41^a on one side of the bar 24, and an extension 47, somewhat longer in length than the finger 46 which cooperates with the step-down portion 42^a of the clip on the opposite side of the bar, the parts operating and producing the same result, namely, the double tripping of the valve to effect a variable sound simulating the cry of "Ma-Ma". Certain features of the invention I have disclosed in my co-pending application Ser. No. 589,290 filed September 20, 1922 (Patent 1,463,008 granted July 24, 1923).

While I have illustrated and described my invention with some degree of particularity, I realize that in practice various alterations therein may be made. I therefore reserve the right and privilege of changing

the form of the details of construction or otherwise altering the arrangement of the correlated parts without departing from the spirit of the invention or the scope of the 5 appended claims.

Having thus described my invention what I claim as new and desire to secure by United States Letters Patent is:—

1. A sound producing device having a 10 tubular bellows, a relatively fixed head closing one end of the bellows, a relatively movable weighty head closing the other end of the bellows, a guide rod extending through the bellows and fixed with respect 15 to the fixed head and on which the weighty head is adapted to slide for guiding said movable weighty head in its movement toward and from the fixed head to compress and distend the bellows, a reed carried by one 20 of said heads and adapted to be operated by the bellows, an opening through which the sound from the reed is adapted to issue, a pivoted valve for said opening and means carried by said guide rod for operating said 25 pivoted valve.

2. A sound producing device having a 30 tubular casing, a tubular bellows in said casing, a head closing one end of the bellows and fixed with respect to the casing, a weighty head closing the other end of the bellows and movable by gravity back and forth in the casing to compress and distend the bellows, a reed carried by the said movable head and adapted to be operated by the 35 bellows, an opening through which the sound from the reed is adapted to issue, a pivoted valve for controlling the issuance of sound from said opening, a guide rod fixed with respect to the casing and extending 40 through the bellows substantially axially thereof, and means on said guide rod for causing the operation of said valve responsive to the operation of said bellows.

3. A sound producing device having a 45 bellows, a head closing one end of the bellows, a weighty head closing the other end of the bellows, a reed fixed with respect to said weighty head and adapted to be operated by the bellows, an opening through 50 which the sound from the reed is adapted to issue, a guide member fixed with respect to the other head and extending through the bellows and the weighty head to guide the latter in its movement toward and from the 55 other head to compress and distend the bellows, a pivoted valve supported independently of the said member and acting to control said opening, and means whereby said guide member controls the operation of said 60 valve responsive to the operation of said bellows.

4. A sound producing device having a 65 bellows, a head closing one end of the bellows, a weighty head closing the other end of the bellows, a reed fixed with respect to

said weighty head and adapted to be operated by the bellows, an opening through which the sound from the reed is adapted to issue, a guide member fixed with respect to the other head and extending through the 70 bellows and the weighty head to guide the latter in its movement toward and from the other head to compress and distend the bellows, a pivoted valve supported independently of the said member and acting to control said opening and means on said guide rod for causing the valve to be opened a plurality of times during one continuous movement of one head with respect to the other head. 75

5. A sound producing device having a 80 bellows, a head closing one end of the bellows, a weighty head closing the other end of the bellows, a reed fixed with respect to said weighty head and adapted to be operated by the bellows, an opening through which the sound from the reed is adapted to issue, a guide member fixed with respect to the other head and extending through the bellows and the weighty head to guide the latter in its movement toward and from the other head to compress and distend the bellows, a pivoted valve supported independently of the said member and acting to control said opening, and means comprising a 85 projection on opposite sides of said guide rod, for directly engaging said valve to operate the valve a plurality of times during one operation of the bellows. 90

6. A sound producing device having a 95 bellows, a head closing one end of the bellows, a weighty head closing the other end of the bellows, a reed fixed with respect to one head and adapted to be operated by the bellows, an opening through which the sound from the reed is adapted to issue, a member fixed with respect to the other head and extending through the bellows and the first head, a valve supported independently of the said member and acting to control said 100 opening, and means whereby said member controls the operation of said valve during the operation of the bellows. 105

7. A sound producing device having a 110 bellows, a head closing one end of the bellows, a weighty head closing the other end of the bellows, a reed fixed with respect to said weighty head and adapted to be operated by the bellows, an opening through 115 which the sound from the reed is adapted to issue, a guide member fixed with respect to the other head and extending through the bellows and the weighty head to guide the latter in its movement toward and from the other head to compress and distend the bellows, a valve supported independently of the 120 said member and acting to control said opening, and means on said guide member for actuating said valve responsive to the operation of the bellows. 125

8. A sound producing device having a tubular bellows, a head closing one end of the bellows, and a head closing the other end of the bellows, the bellows being turned under the edge of one of said heads, a member outside of the bellows and secured to said last mentioned head and acting to clamp the turned under end of the bellows between faces on said head and member, and a reed fixed with respect to one of said heads and

operated by air forced past the same by operation of the bellows, a guide rod fixed with respect to the other head and extending through the bellows, an opening through which the sound from the reed is adapted to issue, a valve for controlling said opening and means on the guide rod for controlling the operation of said valve. 15

In testimony whereof I affix my signature.

MATTEO DE CESARE. [L. s.]
